UNITED STATES PATENT OFFICE.

SIDNEY GEORGE BROWN, OF LONDON, ENGLAND.

TELEPHONE-RELAY.

1,128,943.

Specification of Letters Patent. Patented Feb. 16, 1915.

Application filed January 3, 1912. Serial No. 669,151.

To all whom it may concern:

Be it known that I, SIDNEY GEORGE BROWN, a subject of the King of Great Britain, residing at 4 Great Winchester street, 5 in the city and county of London, England, have invented certain new and useful Improvements Relating to Telephone-Relays, of which the following is a specification.

This invention relates to telephone relays, 10 the chief object being to provide a compact efficient instrument of this kind, and in particular a reliable and highly sensitive form of variable resistance device for inclusion in the local circuit.

15 The type of variable resistance device I employ is one in which, while variations in the line current are causing corresponding variable effects in the resistance of the device in the usual way, the current in the 20 local circuit is utilized to maintain the variable resistance in a microphonic condition, with the result that an extremely sensitive regulation of the microphonic condition of the resistance is maintained and an efficient 25 relay action is obtained. One practical form of variable resistance device of this kind comprises carbon granules inclosed between two contact pieces one of which is stationary and the other attached to a vibratory armature influenced by coils through which the 30 line current passes and also by coils through which the local current passes. In order to obtain the highest efficiency of transmission of the vibratory movements of the armature 35 from the latter to the variable resistance device it is necessary for the contact piece carried by the armature to be small in terminal area. Hence from the mechanical point of view the variable resistance device, and 40 hence also the column of carbon granules, should be small in diameter or cross section. From the electrical point of view, however, the value of the maximum resistance that the carbon granules should offer 45 has a limit, and in the case of a resistance device of small diameter or sectional area this resistance is liable to be exceeded if the mere dead weight of the granules is relied upon. According to the present invention, 50 therefore, the variable resistance device is of small diameter or sectional area, its excessive resistance is reduced by exerting an initial pressure upon the microphonic material contained in it, and the microphonic character of this material is automatically main-

tained by the effect of the local current as already described. The conductivity of the variable resistance is therefore such that the normal current passing through it is greater than that which it could convey by reason 60 merely of the dead weight of the granules, and the regulation of this increased conductivity is effected electrically. A convenient form of the device comprises a layer or a number of separated layers of granular material, preferably carbon, the thickness of any one layer being approximately the thickness of a single granule, so that, since the layer is only one granule deep, the defect 65 commonly existing in granular contact devices due to "packing" of the granules is avoided. The most effective parts of granules are their points and edges, and when a considerable mass of granules is used the 70 particles tend to take up positions alongside one another, and to wedge into one another, whereas if a single layer or a number of separated layers one granule deep is employed, the full effect of the "end-on" 75 positions of the granules, or in other words the maximum effect of their points and edges, is obtained. Although metallic particles may 80 be used as the granular material, I find fine carbon grains to yield excellent results. The contact pieces between which the one or 85 more thin layers of granular material are situated may comprise carbon or metal 90 stops, one being normally stationary, although manually adjustable for the purpose of setting the instrument, the other being mounted on a vibratory reed serving as the armature of the usual polarized electromagnet. In order to keep the granules in position laterally, a short sleeve, preferably of 95 glass and having a limited axial freedom of movement, may be employed.

It is found advantageous in practice for the movable contact and hence also the axis of the whole resistance device to be eccentric with respect to the axis of the magnetic 100 field that influences the armature, the eccentricity or displacement being toward the fixed end of the armature.

In addition to the electromagnet windings 105 through which the line currents pass, and the electromagnet windings through which the local current passes for maintaining the microphonic condition of the variable resistance device, the electromagnet may also have wound upon it counteracting windings 110

that are brought into action only if the attracting force exerted upon the armature by the other windings becomes excessive, the effect of these counteracting windings then being to neutralize this attracting force.

In order that the invention may be clearly understood and readily carried into effect, I will now describe the same more fully with reference to the accompanying drawings, in which:—

Figure 1 is a diagrammatic plan of my improved relay and its connections to the line and to a local circuit. Fig. 2 is a diagram of electrical connections in the local circuit including the connections for the counteracting coils. Fig. 3 is a side elevation, Fig. 4 a plan, and Fig. 5 a sectional elevation of the complete instrument to full size. Fig. 6 is an enlarged detail longitudinal section of one form of the variable resistance device, and Fig. 7 is a modified form of this device. Fig. 8 is a much enlarged cross section of a disk that may be employed in the construction of a further modified form of variable resistance device, as hereinafter described. Fig. 9 is a front elevation and Fig. 10 a side elevation, with certain parts removed, of a modified form of the relay, in which two variable resistance devices are used. Fig. 11 is a diagram of connections for the device shown in Figs. 9 and 10. Figs. 12, 13 and 14 illustrate a further modified construction of relay hereinafter referred to.

A A are the line wires leading to and from the line current windings A', and B B are the wires leading to and from the local current windings B'.

C is the polarized electromagnet. The windings B' are wound around upright cores C', which are secured to the ends of the electromagnet C; the counteracting windings hereinbefore referred to, and shown in Fig. 2 by the reference letters B'', are also wound upon the cores C'. These cores may be inclosed in copper sheathing c in order that eddy currents set up in the sheathing may tend to neutralize the self induction of the superposed windings.

The windings A' are wound upon laminated pole pieces C², secured horizontally by brass screws to the upper ends of the cores C'. The free ends of the pole pieces C² are close together and are situated behind the armature D.

E is the variable resistance device, this being included in the local circuit which includes also the windings B', switch B², source of electric current B³, detector B⁴, and transformer winding B⁵. The other transforming winding B⁶ is included in the actual circuit of the telephone receiver B⁷. Obviously the telephone might be connected directly in the local circuit, and is in fact so shown in Fig. 2.

The armature D carries the contact piece D' of the pair of contact pieces D', E', (Fig. 6) of the variable resistance device E, which may conveniently be .08 to .1 of an inch in diameter. The contact piece E' forms part of a block E² (Fig. 4) which is adjustably mounted in a bearing E³ carried by an insulating bed plate E⁴. This insulating bed plate is capable of longitudinal adjustment by means of the thumb screw E⁵ around which is coiled a stiff spring E⁶ (Figs. 4 and 5). Between the contact pieces D', E', the one or more thin layers of microphonic material are inclosed. The particular construction of variable resistance device shown in Figs. 1-5, and in detail in Fig. 6, comprises in addition to the contact pieces D', E', three thin layers of carbon grains separated by thin disks E⁷ of carbon or metal faced with carbon. Each thin layer is only one grain deep approximately. The grains are inclosed by a sleeve E⁸ of practically inextensible material in order to prevent lateral expansion and thereby insure an efficient axial transmission of variations in pressure. Glass is found satisfactory for this purpose and has the additional advantage of allowing of examination of the device from the outside. The longitudinal axis of the device as a whole is displaced relatively to the axes of the electromagnet pole pieces C² the displacement being toward the fixed end of the armature D. It is found in practice that by locating the device E in this way, the vibrations of the armature are transmitted to the device more efficiently than if the latter were located actually at the free end of the said armature or in the plane of the axes of the electromagnet pole pieces. The armature itself may take the form of a steel reed the free end of which may be of steel or of soft iron. An intermediate part of the reed is preferably cut away as at D² in order to impart the requisite resiliency to it. The said reed is held down upon a rounded bridge piece D³ by two screws D⁴, one on each side of the bridge piece.

In the modified form of resistance device shown in Fig. 7, the disks E⁷ extend outwardly beyond the layers and serve as radiating flanges to more quickly dissipate the heat produced in the device when in operation. In this case the sleeve is substituted by mere rings of any suitable somewhat elastic material. The disks E⁷ instead of having plain surfaces as shown, might have surfaces specially roughened in order to interlock to some extent with the grains and more effectively hold them in place; the roughening of the said surfaces may be done symmetrically, for instance by ruling grooves E⁹ upon them as shown in Fig. 8, the grooves on one surface being ruled in a transverse direction with respect to those on the other surface. 130

- If two or more such disks are piled together with their grooves crossing one another, a large number of contact points will be obtained, thus producing the equivalent of a layer of grains, with, however, the advantage that the points of contact would not be liable to change in position and would be symmetrically arranged relatively to one another.
- 10 The manner in which the instrument works will be readily understood. The screw is adjusted to put a degree of pressure upon the variable resistance device such that, when the switch is closed, the attracting force of the local circuit windings will move the electromagnet armature sufficiently to reduce the pressure enough to establish the microphonic condition of the device. Variations in the strength of the current traversing the line windings will then cause variations in the resistance of the device but such variations by reason of the copper sheathing on the upright cores of the magnet do not affect the local regulation, with the result that a very sensitive regulation is maintained, and a sensitive relay action obtained.
- Referring now to Fig. 2, it will be seen that the reed D is provided at its free end with a tongue D^5 reaching between two stops D^6 and D^7 . Under normal conditions of working the amplitude of vibration of the reed is not sufficient to produce contact between the tongue D^5 and the stops D^6 , D^7 , but when the attraction of the electromagnet pole pieces C^2 becomes excessive this contact takes place; the effect is to complete the circuit of one or other of the counter-acting windings B^x , B^x , which, together with a resistance D^8 , are included in circuits adapted to derive current from the battery B^3 as clearly shown in the figure. The windings B^x , B^x , are wound co-axially with the windings B' , B' , and are arranged to reduce or increase respectively the strength of the magnetic circuit, thus preventing the reed D from becoming excessively attracted, or repelled, by reason of any excessive disturbing relay currents or currents arising from outside sources and passing through the instrument.

In the modified construction of relay shown in Figs. 9 and 10, and diagrammatically in Fig. 11, it is seen that there are two variable resistance devices E^o and E^x , arranged one upon each side of a common armature D^x . A^o , A^o , are the line current windings, B^o , B^o , the local current windings, and F^o , F^o , are the counteracting windings, which may not however be required. The armature D^x is normally kept in a mid-position by the equal attraction of the two similar cores or pole pieces E^{10} , which are capable of adjustment by means of the thumb screws E^{11} . The requisite pressure exerted upon the carbon granules in the resistance devices E^o , E^x is manually adjusted by the spring controlled thumb screws E^{12} . In this case however the microphonic condition of the devices, instead of being established by the local windings, is established by the manual adjustment of the screws E^{12} . In other words the initial pressure applied to the granules is not in this case sufficient to impair their microphonic property, which property is, in the constructions above described, restored by the partial relief of the pressure brought about by the local windings; in the present construction the pressure applied is only sufficient to put the granules into their most sensitive microphonic condition; any disturbance, however, tending to move the armature D^x excessively and thereby upset the microphonic condition is checked by the action of the local current windings, since an excessive drop or rise in the conductivity of the granules causes a corresponding decrease or increase in the magnetic influence of these windings. Briefly stated, the local current windings, although not establishing the microphonic condition of the devices E^o , E^x , serve to maintain them in that condition.

In a further modified form of the instrument shown in Figs. 12, 13 and 14, the armature D^o , instead of being held down, by screws, upon a rounded bridge piece as in Figs. 2, 3 and 5, and being thereby rendered adjustable in position relatively to the free-ends of the electromagnet pole pieces C^2 , is rigidly and permanently fixed to the framework of the instrument, and the adjustment of the small space between the armature and the pole pieces is effected by moving the latter. For this purpose the upright cores C' of the polarized magnet are severed as shown by the dotted lines C^x , so that the portions attached to the pole pieces C^2 , together with the said pole pieces and the windings A' thereon, can be bodily advanced or retracted relatively to the armature D^o . In the drawings these parts are shown mounted upon a bed plate C' capable of being traversed by a screw. In order that the magnetic circuit of the magnet may not be detrimentally affected, the C-shaped magnet C and the lower portions of the upright cores C' may be mounted upon upwardly thrusting springs C^{xx} adapted to keep the severed portions of the cores in firm contact with one another.

What I claim and desire to secure by Letters Patent of the United States is:

1. A telephone relay, comprising a magnet, line current windings thereon, a vibratory armature associated with said magnet, a granular microphone of the order of .1 of an inch in diameter, one contact piece of the microphone being attached to the aforesaid armature, means for initially applying pressure upon the microphonic material, and electrical means for relieving the pressure

and thereby establishing and maintaining the microphonic condition of the microphone.

2. A telephone relay, comprising a magnet, line current windings thereon, a vibratory armature associated with said magnet, a granular microphone of the order of .1 of an inch in diameter, one contact piece of the microphone being attached to the aforesaid armature, means for initially applying pressure upon the microphonic material, and windings on the magnet connected in series with the microphone.

3. A telephone relay, comprising a magnet, line current windings thereon, a vibratory armature associated with said magnet, a granular microphone of the order of .1 of an inch in diameter, one contact piece of the microphone being attached to the aforesaid armature, means for initially applying pressure upon the microphonic material, windings on the magnet connected in series with the microphone, and means whereby any excessive magnetic influence upon the armature automatically throws into action a counteracting influence.

4. A telephone relay, comprising a magnet, line current windings thereon, a vibratory armature associated with said magnet, a granular microphone of the order of .1 of an inch in diameter, one contact piece of the microphone being attached to the aforesaid armature, means for initially applying pressure upon the microphonic material, windings on the magnet connected in series with the microphone, windings on the magnet wound counteractingly with respect to the line windings, and means arranged for cooperation with the armature to complete the circuit of the counteracting windings when the armature tends to vibrate excessively.

5. A telephone relay, comprising a magnet, line current windings thereon, a vibratory armature associated with said magnet, a granular microphone of the order of .1 of an inch in diameter, one contact piece of the microphone being attached to the aforesaid armature, means for initially applying pressure upon the microphonic material, windings on the magnet connected in series with the microphone, windings on the magnet wound counteractingly with respect to the line windings, stops connected electrically with the counteracting windings, and an extension on the vibratory armature for cooperation with said stops.

6. A telephone relay comprising a polarized electromagnet, line current windings thereon, a metal reed serving as armature to said electromagnet, a granular carbon microphone of the order of .1 of an inch in diameter, one contact piece of the microphone being attached to the aforesaid armature, means for adjusting the other contact piece to apply pressure to the granules,

windings on the electromagnet connected in series with the microphone, and means for limiting the vibratory movements of the reed.

7. A telephone relay, comprising a polarized electromagnet, electromagnet windings forming part of the line circuit, a resilient reed serving as armature to said electromagnet, a contact piece secured to the aforesaid reed, an oppositely situated normally stationary contact piece, separated layers of granular material located between the contact pieces, each layer being of the order of .1 of an inch in diameter and approximately one granule thick, means inclosing the granules laterally, means for adjusting the normally stationary contact piece, and electromagnet windings forming part of a local circuit including the aforesaid contact pieces and layers of granular material.

8. A telephone relay, comprising a polarized electromagnet, electromagnet windings forming part of the line circuit, a resilient reed serving as armature to said electromagnet, a contact piece secured to the aforesaid reed, an oppositely situated normally stationary contact piece, separated layers of carbon granules located between the contact pieces, each layer being of the order of .1 of an inch in diameter and approximately one granule thick, thin conducting disks separating the layers, an axially movable glass sleeve inclosing the granules and disks laterally, means for adjusting the normally stationary contact piece, and electromagnet windings forming part of a local circuit including the aforesaid contact pieces and layers of granular material.

9. A telephone relay, comprising a polarized electromagnet, an electromagnet armature, electromagnet windings forming part of the line circuit, electromagnet windings forming part of the local circuit, a granular carbon microphone having a contact piece movable with the aforesaid electromagnet armature and a granule chamber of the order of .1 of an inch in diameter, electromagnet windings acting to counteract the effect, upon the armature, of the other windings, means coöperating with the armature for controlling the circuit of the counteracting windings, and means for exerting an initial pressure upon the granules.

10. A telephone relay comprising a horizontal polarized electromagnet, upright cores thereon, local current windings upon the cores, converging pole pieces secured horizontally to the cores, line current windings upon the pole pieces, a resilient reed serving as electromagnet armature, a granular carbon microphone having a contact piece movable with the reed and a granule chamber of the order of .1 of an inch in diameter, and means for exerting an initial pressure upon the granules.

11. A telephone relay, comprising a horizontal polarized electromagnet, upright cores thereon, local current windings upon the cores, converging pole pieces secured horizontally to the cores, line current windings upon the pole pieces, a resilient reed serving as electromagnet armature, a granular carbon microphone having a contact piece movable with the reed and a granule chamber of the order of .1 of an inch in diameter, means for exerting an initial pressure upon the granules, and means for adjusting the air gap between the above mentioned pole pieces and the reed.
12. A telephone relay comprising a polarized electromagnet, upright cores thereon, local current windings upon the cores, converging pole pieces secured horizontally to said cores, line current windings upon the pole pieces, an electromagnet armature, a contact piece secured to the aforesaid armature, an oppositely situated normally stationary contact piece, separated layers of carbon granules located between the contact pieces, each layer being of the order of .1 of an inch in diameter and approximately one
- 5 granule thick, thin carbon disks separating the said layers, an axially movable glass sleeve inclosing the granules and disks laterally, and means for adjusting the normally stationary contact piece for exerting an initial pressure upon the granules.
13. A telephone relay, comprising a polarized electromagnet, upright cores thereon, copper sheathing around the cores, local current windings upon the sheathing, laminated pole pieces secured horizontally to the cores, line current windings upon the pole pieces, an electromagnet armature, a granular carbon microphone included in the local circuit and having a granule chamber of the order of .1 of an inch in diameter, one contact piece of the device being fixed to the aforesaid electromagnet armature, and means for exerting an initial pressure upon the granules.
- In testimony whereof I affix my signature in presence of two witnesses.
